J. A. McDONALD,
RAIL JOINT.
APPLICATION FILED AUG. 5, 1919.

1,356,931.

Patented Oct. 26, 1920.

UNITED STATES PATENT OFFICE.

JOHN A. McDONALD, OF ARANSAS PASS, TEXAS.

RAIL-JOINT.

1,356,931.

Specification of Letters Patent. Patented Oct. 26, 1920.

Application filed August 5, 1919. Serial No. 315,451.

To all whom it may concern:

Be it known that I, JOHN A. McDONALD, a citizen of the United States, residing at Aransas Pass, in the county of San Patricio, State of Texas, have invented certain new and useful Improvements in Rail-Joints; and I do hereby declare the following to be a full, clear, and exact description of the invention, such as will enable others skilled in the art to which it appertains to make use of the same.

This invention relates to joints for the meeting ends of rails, and more especially to those of that type known as scarf joints; and the object of the same is to produce a joint of this character so constructed that as the wheel crosses the same the load on one rail-end will be transferred to and sustained by the other rail-end, first partially and then entirely, with the result that the sagging of parts at this point will be avoided and the rail caused to stand as firm at the joint as at any other place throughout its length.

Another object is to prevent vertical or lateral displacement or disengagement of the rails from each other, even though the connecting bolts should become loose or broken or be entirely omitted.

With these ends in view the invention consists broadly in removing half of each rail-end so as to leave a projecting tongue, the same being undercut to produce two shoulders adapted to coact with mating steps on the other rail, and in forming certain of these steps with tongues and grooves to prevent lateral displacement while still permitting expansion and contraction longitudinally.

In the accompanying drawings:

Fig. 1 is a plan view of this joint with the rail-ends connected.

Fig. 2 is a similar plan with the rail-ends slightly separated and all bolts omitted.

Fig. 3 is a side elevation with the rails separated.

Fig. 4 is a perspective view of one rail-end, and Figs. 5 and 6 are sectional views through two rails.

The rail-ends are of exactly the same construction, with the result that when they are turned so as to meet they will engage each other as shown in Fig. 1. For this reason a description of one rail-end will suffice. The body of the rail at the left of Fig. 3 has the usual ball B, web W, and base flanges F, and it is held to the ties by appropriate

fastening means engaging said flanges. At each end the rail is practically bisected to produce a tongue 1, the line of bisection starting at the extremity of the rail at the point 2, extending thence along the center of the ball at 3 back to the point 4, there making a right angle and carried to one side of the ball at the point 5. Thus the near half of the rail in Fig. 3 is cut away to form a recess which is shaped to receive the tongue of the companion rail. The inner end of this recess is composed of a wall 6 leading vertically downward to the point 5, thence the material is carried forward in a step 7 which is grooved at 8 as seen in dotted lines in Fig. 3 and in full lines in Fig. 4, thence the material is carried again downward at 9 and carried forward in a second step 10, and finally the material is carried again downward at 11 to the bottom of the base flange F, the side 12 of this last step being preferably flat and standing substantially in the plane of the side of the other step as shown. So much for the construction at the inner end of the recess which is produced by cutting away the material to form the tongue 1.

From the point 2 at the outer end of the tongue the line to the point 15 indicates the thickness of the end of the tongue, and is of course half the width of the ball B of the rail. From this cross line the end of the point extends downward in a wall 16, thence horizontally inward in a shoulder 17 which along its inner edge has a depending tongue 18, thence downward at 19, horizontally inward in a second shoulder 20, and again downward at 21, the outer side of the face 21 being shaped as at 22 to mate with the side 12 described above. Finally the tongue has an opening 27 above the step 7 and an opening 28 above the shoulder 20.

Fig. 2 shows two rail-ends as thus constructed, slightly separated, and Fig. 1 shows them engaged with each other. It will be obvious that when the faces of the two tongues are brought together and one rail slid longitudinally toward the other, each tongue 18 slides into a groove 8 at the time that its shoulder 17 slides over the step 7 and at the time that the shoulder 20 slides over the stop 10. At the time the faces 9 and 19 abut, the faces 11 and 21 will abut and the openings 27, 28 in one rail will register with the openings 28, 27 of the other rail. These openings are shown round but they may be elongated or may be made

large enough for the rather loose reception of the fastening bolts 30 which are applied to connect the rail-ends to each other, the obvious purpose being to permit expansion 5 and contraction of the rails. During this action one rail-end slides a little toward or away from the other, as the engagement of the several shoulders with their respective steps permits, and even the engagement of 10 the tongue 18 with the groove 8 permits. Yet the latter prevents the lateral separation of the tongues of the two rails until and unless they shall withdraw from each other so far longitudinally that the tongue and 15 grooves become disengaged, and it is my intention to have these parts so long that they will not disengage by contraction. Each shoulder rests upon its step, and each 20 step is integral at one end with the tongue along which it is cast. Therefore, when a wheel carrying a heavy load passes over this rail joint, the load passes first from the ball B on to the tongue 1 where the weight is divided between this tongue and that of 25 the mating rail, and by the latter it is conveyed to the steps of the first rail. As the wheel progresses, the load on the tongue of the rail being left is conveyed to the steps on the rail being approached, and eventually 30 the wheel passes fully onto the ball B of the last-named rail, and on its way. Thus it will be seen that this rail joint accomplishes the objects first pointed out above, may be very easily mated with a like joint in a companion rail, and is economical in manufacture because the ends of the rails are made in duplicate. While the face of the tongue 35 1 has been shown as cut off on a line following the transverse center of the rail, it

is not impossible that this line could stand 40 a little oblique. Other changes and adaptations are possible but need not be suggested.

What is claimed as new is:

1. A rail joint comprising duplicate rail-ends whereof each is cut vertically and longitudinally through the ball of the rail 45 downwardly to produce a tongue at one side and a recess at the other, the base of the recess having two upwardly facing steps and one of them provided alongside the tongue 50 with a longitudinal groove, and the tongue having two downwardly facing shoulders and one of them provided with a longitudinal tongue, these elements adapted to mate with corresponding elements of the 55 companion rail-end, and means for locking the tongues face to face.

2. The combination of two rail sections, each of said rail sections being cut away forming a tongue and having a longitudinal 60 groove alongside the rear portion of said tongue and having an angular portion alongside the tongue below said groove and inwardly from the outer edge of the flange of the rail, and the end portion of each rail 65 section being undercut forming a flat under face and a longitudinal depending tongue, and the lower portion of the tongue below said undercut portion being further undercut forming an angular recess in the bot- 70 tom of the tongue.

In testimony whereof, I affix my signature, in the presence of two witnesses.

JOHN A. McDONALD.
